Primary Examiner — David G Muller(74) *Attorney, Agent, or Firm* — Servilla Whitney LLC(57) **CLAIM**

The ornamental design for a respiratory valve, substantially as shown and described.

DESCRIPTION

FIG. 1 is a front perspective view of a respiratory valve;
FIG. 2 is a rear perspective view of the respiratory valve;
FIG. 3 is a front view of the respiratory valve;
FIG. 4 is a left side view of the respiratory valve;
FIG. 5 is a rear view of the respiratory valve;
FIG. 6 is a top view of the respiratory valve; and,
FIG. 7 is a bottom view of the respiratory valve.
Portions of the drawings shown within broken lines form no part of the claimed design.
